UNITED STATES PATENT OFFICE

106,135

DESIGN FOR A CASING FOR BOILER BURNER UNITS OR THE LIKE

Mora S. Hall, Carroll County, Md., assignor to
May Oil Burner Corporation, a corporation of
Maryland

Application August 17, 1936, Serial No. 64,430

Term of patent 14 years

To all whom it may concern:

Be it known that I, Mora S. Hall, a citizen of the United States and residing in Carroll County, in the State of Maryland, have invented a new, original, and ornamental Design for Casing for Boiler Burner Units or the like, of which the following is a specification, reference being had to the accompanying drawing, forming a part thereof.

Figure 1 is a front perspective view of the casing for boiler burner units or the like showing my new design. The rear of the casing is substantially plain and the other side substantially the same as the side shown.

Figure 2 is a fragmentary horizontal section through the front wall of the casing, the section

being taken along line 2—2 of Figure 1 showing the contours of the corner rails and of the wall panels.

The characteristic features of my design reside in the design as shown, the front of which has relatively narrow and wide vertical panels on either side of a central panel harmonizing with the top panel arrangement, the narrow front panels being shaded to indicate contrasting color effect.

I claim:

The ornamental design for a casing for boiler burner units or the like, substantially as shown and described.

MORA S. HALL.
